Specification for Design.

Patented Nov. 4, 1919.

Application filed April 14, 1919. Serial No. 290,104. Term of patent 14 years.

To all whom it may concern:

Be it known that we, PAUL McHALE and THOMAS J. JUDGE, citizens of the United States, both residing at Worcester, in the county of Worcester and State of Massachusetts, have invented a new, original, and ornamental Design for a Plank for Meats and Fish, of which the following is a specification, reference being had to the accompanying drawing, forming part of this specification, in which—

Figure 1 is a top plan view of the plank showing our new design and

Fig. 2 is a perspective view thereof.

We claim:

The ornamental design for a plank for meats and fish, as shown.

In testimony whereof we have hereunto affixed our signatures.

PAUL McHALE.
THOMAS J. JUDGE.
